Primary Examiner—Brian N. Vinson[57] CLAIM

The ornamental design for a hair bow and head band hanger, as shown and described.

DESCRIPTION

FIG. 1 is a front elevational view of a hair bow and head band hanger showing my new design;

FIG. 2 is a left side elevational view thereof, the right side being a mirror image of that shown;

FIG. 3 is a rear elevational view thereof;

FIG. 4 is an enlarged top plan view thereof;

FIG. 5 is an enlarged bottom plan view thereof;

FIG. 6 is an enlarged, fragmentary left side elevational view of the central portion thereof; and,

FIG. 7 is an enlarged, fragmentary left side elevational view of the bottom portion thereof.

FIG. 7
